United States Patent Office

Des. 195,694
Patented July 16, 1963

195,694

CURRENCY CHANGER

James E. Jones, University City, and Walter E. Moore,
Bel Air, Mo., assignors to National Rejectors, Inc.,
St. Louis, Mo., a corporation of Missouri

Filed Oct. 11, 1962, Ser. No. 72,069

Term of patent 14 years

(Cl. D52—4)

FIG. 2.

FIG. 3.

FIG. 1.

FIG. 1 is a perspective view of a currency changer, embodying our new and ornamental design,

FIG. 2 is an elevational view of the left-hand side of the currency changer of FIG. 1, and

FIG. 3 is an elevational view of the rear of the currency changer of FIG. 1.

The right-hand side of the currency changer of FIG. 1 is a mirror image of the left-hand side of that currency changer.

We claim:

The ornamental design for a currency changer, as shown and described.
